UNITED STATES PATENT OFFICE.

WALLACE C. HILL, OF UTICA, NEW YORK.

ARM-SHIELD.

1,147,630.

Specification of Letters Patent. Patented July 20, 1915.

Application filed August 31, 1914. Serial No. 659,310.

To all whom it may concern:

Be it known that I, WALLACE C. HILL, a citizen of the United States, residing at Utica, in the county of Oneida and State of New York, have invented certain new and useful Improvements in Arm-Shields, of which the following is a specification, reference being had therein to the accompanying drawing.

10 My invention relates to an arm shield, and I declare the following to be a full, clear, concise and exact description thereof sufficient to enable anyone skilled in the art to which it appertains to make and use the 15 same, reference being made to the accompanying drawings in which like reference characters refer to like parts throughout the specification.

The object of the invention is to provide a 20 simple, efficient device that may be worn upon the back of the arm of a chauffeur, whereby to protect his arm from the blow of a crank handle caused by the back kick of the motor on an automobile, motor boat 25 or other like vehicle. The blows are delivered with such force as to break a person's arm, there being no chance of escaping the same because of the velocity of movement of the crank handle, when the back 30 kick unexpectedly occurs. The shield is constructed so that it can be worn conveniently upon a person's arm underneath or over the coat sleeve at his option.

These objects are attained by the mechanism illustrated in the accompanying drawings in which:

Figure 1 is a plan view looking down on the back thereof of a modified construction; Fig. 2 is a vertical section enlarged, taken 40 on the line 6—6 of Fig. 5; Fig. 3 is an enlarged fragmentary view showing a section taken on the line 6—6 of Fig. 5.

Referring to the drawings in a more detailed description thereof, the body of the 45 shield is made preferably of any suitable metal and is constructed substantially upon the segment of a cylinder, whereby to adapt the same to the general conformation of the human forearm. The body is of sufficient 50 length to extend approximately from the middle of the back of the hand or the knuckles to the elbow, and has a portion bent upward at 2, whereby to form a shoulder adapted to ward off any blows that 55 might be directed toward the fingers. There is a bent up portion, also at 3, where-

by to permit the body to slide easily along the arm, without injuring the same, especially when assembling the shield to the arm under the coat sleeve.

Extending laterally from the body and near either end thereof, are the lips 4, which are integral with said portion. The corner of the free ends of the lips 4 are rounded off, as at 5, whereby not to leave any sharp edges to do injury to the arm. The lips 4 are made of thin metal, so as to be more or less pliable to thereby readily conform to the shape of the human arm in order to fit snugly thereagainst, as well as to prevent 70 the shield from creeping around the arm. Furthermore, the shield is held in proper position on the arm by the straps 6, which are riveted to the lips 4 at 7 and are held together in pairs with any desired degree of 75 tightness against the arm by the knuckles 8.

The interior of the body portion, the lips 4, and the straps 6, or the surface that lies adjacent the arm is lined with a padding of felt or other soft yielding material 10, 80 whereby to aid in lessening the effect of the blow upon the shield.

The serviceableness of the device is derived by disposing the body portion upon the arm, so that the same will extend from 85 about the location of the center of the back of the hand or the knuckles to the elbow. The straps 6 are then drawn tight, one about the wrist and the other about the arm near the elbow. The upturned portion 3 will aid 90 in assembling the shield to the arm by permitting the same to slide therealong without doing any injury, as before stated. When the shield is thus assembled, a blow directed 95 in the vicinity of the fingers will be warded off by the upturned portion 2, and a blow upon the forearm will be neutralized by the hard surface of the body in combination with the padded lining 10.

The body of the shield embodies the parts 100 15 and 16, which are adapted to slide upon each other, whereby the shield can be extended to fit any size of the arm. The part 15, which is of less length than the part 16 has its lateral edges bent over as at 20—20 105 to form run ways for the sliding reception of the lateral edges 21—21 of the part 16. The parts 15 and 16 are held in adjusted longitudinal position with reference to each other, when the straps are not engaging the 110 arm, by the plunger 25 housed in a recess 26 formed in the part 15. The plunger 25

is actuated normally downward against the surface of the part 16 by a coiled spring 27, whereby to contact with said surface with sufficient force to hold the parts 15 and 16 in the aforesaid relation, and yet permit them to be moved manually. Furthermore, the parts 15 and 16 are prevented from sliding free of each other by the blocks 30—30 fastened to the part 15 and the blocks 31 fastened to the part 16 in such a manner as to abut against each other when the parts 15 and 16 have been drawn or extended to the maximum limit.

The ends having the upturned portions 2 15 and 3, are rounded off upon a horizontal plane, whereby to permit of the free and easy movements of the portions of the hand and arm adjacent the said ends.

The part 15 of the body portion is made 20 shorter than the part 16 in order that it may be easily adjusted in a longitudinal manner to cover the back of the hand.

Having thus described my invention, what I claim as new and desire to secure by Letters Patent is:

1. In an arm shield, parts slidably mounted in relation to each other, means for holding said parts in given adjusted position with reference to each other, and straps 36 for holding said parts to the forearm.

2. In an arm shield, a body portion comprising parts slidably mounted with relation to each other, one of said parts having its edges bent over to form guideways for the sliding reception of the edges of the other part, a plunger disposed in a recess in one of said parts and adapted to contact with the surface of the other part, whereby said parts may be held in given adjusted position, and straps for securing said shield to the forearm of a person.

3. In an arm shield, a body portion comprising parts slidably mounted with relation to each other, one of said parts having its edges bent over to form guideways for the sliding reception of the edges of the other part, a plunger disposed in a recess in one of said parts and adapted to contact with the surface of the other part, whereby said parts may be held in any given adjusted position, means for preventing said parts from being drawn apart, and straps for securing said shield to the forearm of a person.

In testimony whereof I have affixed my signature in the presence of two witnesses.

WALLACE C. HILL.
